(57) **CLAIM**

The ornamental design for an electronics housing, as shown and described.

DESCRIPTION

FIG. 1 is a front view of an electronics housing of the present invention;

FIG. 2 is a side perspective view thereof;

FIG. 3 is an exploded side perspective view of the electronics housing in an open position; and,

FIG. 4 is a rear view thereof.

The broken lines in the drawings are for the purpose of illustrating portions of the electronics housing that form no part of the claimed design.
